UNITED STATES PATENT OFFICE.

JEROME PASINI, OF NEW YORK, N. Y.

SHIP.

Application filed June 3, 1927. Serial No. 196,312.

- The present invention is concerned with the provision of improvements in ships, particularly with the provision of a ship which may be readily located for salvage purposes if it sinks, and which is provided with means for readily guiding the lifting lines from floating cranes or the like into proper engagement with the submerged vessel when it is desired to raise the ship.
- 10 The ship is also provided with life saving devices in the nature of buoyant cabins adapted to remain on the surface of the water or to float to the surface of the water carrying the passengers when the ship sinks.
- 15 Objects of the invention are to provide a ship which will not only result in the saving of lives, but which carries buoys which will facilitate the location of it when sunk, and which will render the salvaging thereof extremely simple.

Other objects of the invention are to provide a ship which will be of substantially conventional appearance, and in which the various life-saving and salvage-expediting apparatus may be embodied without materially increasing the cost of building the ship.

With the above noted and other objects in view, the invention consists in certain novel features of construction and combinations and arrangements of parts, as will be more fully hereinafter set forth and pointed out in the claims. The invention may be more fully understood from the following description in connection with the accompanying drawings, wherein—

Fig. 1 is a diagrammatic view showing a ship embodying the present invention resting on the bottom with the buoyed cabins floating on the surface of the water, the signal buoys afloat and in use to guide the lines of floating cranes into engagement with the ship, so that the latter may be lifted.

Fig. 2 is a top plan view of the ship.

Fig. 3 is a vertical sectional view through one of the buoy and cable chambers taken on the line 3—3 of Fig. 2.

Fig. 4 is a transverse sectional view on the line 4—4 of Fig. 3.

50 Fig. 5 is a sectional detail on the line 5—5 of Fig. 2.

Fig. 6 is a sectional view through one of the buoyant cabins taken on the line 6—6 of Fig. 2.

55 It is to be understood at the outset that

the showing of the present invention is for the most part diagrammatic, and that many structural details have been omitted for the sake of clearness. I have used the reference numeral 10 to designate a ship, the upper 60 deck 11 of which is provided with sills or frames 12 in which passenger cabins 13 are mounted, the sills 12 preventing sliding movement of the cabins as the ship rolls, yet permitting immediate dislodging of the 65 cabin if the ship sinks so that the cabins may float to the surface of the water.

It is to be understood that the cabins which may be provided with doors 14 and portholes 15 are capable of being substantially hermetically sealed, so that there will be no danger of the water rushing in them in case of an accident which results in submerging the ship. Instead, when the ship sinks from the surface of the water to the 75 position shown in Fig. 1, the cabins will remain on the surface and the portholes may be opened or other supplemental means provided for supplying air to the floating cabins.

In most accidents there is ample time for the passengers to gather, for instance in the floating cabins, and remain sufficiently on top of the water when the vessel submerges.

Another feature of the invention is the provision of any desired number of floating hollow signal buoys 16 which rise to the surface of the water after the ship is submerged and mark the spot where the ship rests, so that salvaging vessels may readily 90 locate the sunken vessel. Means is also associated with the signal buoys for guiding lifting lines from a salvaging vessel such for instance as a floating crane into proper engagement with the sunken ship for raising 95 the same.

As indicated in Fig. 1 chambers 17 are provided having open tops which lie approximately flush with the main deck 18 of the ship. Fitted into these chambers are the buoys 16, the buoys being approximately hemispherical in shape and including flanged covers 19 which lie flush with the deck of the ship and which are apertured for the reception of centering pins 20 in the deck 100 so that there will be no danger of the buoys rotating in the chambers 17 or rolling about therein due to the motion of the ship.

Each of the buoys 16 is anchored to one end of a length of line 25, the other end of 110

which is anchored to a chain cable 21. The cable 21 may consist of four connected sections, these sections entering the chamber 17 through suitable openings in a packing gasket 22 arranged under the flange of the buoy 19 and against a shoulder 23 provided near the upper end of the chamber 17. The chains may pass from the usual chain lockers of the ship (not shown) across the deck 18 in grooves 24 and thence downwardly through the gaskets 22 where they are coiled in the bottom of the chamber 17.

It is understood that the openings through which the chains 24 are introduced into the chamber 17 permit water to leak around the buoy when the ship becomes submerged so that the chamber 17 will fill with water and the buoy will float upwardly to the surface.

Under ordinary conditions however, water in the chamber 17 is not desired, and any water accidentally leaking into this chamber from waves which may wash over the deck is removed through a drain pipe 30 and returned overboard by a pump 31.

In order that the buoy 16 may snugly fit chamber 17, chamber 17 is preferably provided with grooves 32 in which various runs of the cable 21 lie.

When the ship sinks and the signal or marking buoys 16 float to the surface, they will carry with them in line 25, and shift the chain cable approximately to the position shown in Fig. 1 with the four runs of the chain converging where they join the line 25.

By virtue of this arrangement, a salvaging vessel such for instance as the floating crane 35 may readily guide hoisting lines 36 into place by the simple expedient of passing split rings 37 around the lines 25, connecting an anchor or other hook 38 to the rings, and letting the rings slide down the lines 25 until the anchors may be engaged with the chains 21. In Fig. 1 I have shown one hoisting line from the floating crane engaged with the chains 21 and another anchor being slid down the guide line 25 into position to engage the ship prior to raising the same.

Obviously, various changes and alterations might be made in the general form and arrangement of the parts described without departing from the invention. Hence I do not wish to limit myself to the details set forth, but shall consider myself at liberty to make such changes and alterations as fairly fall within the spirit and scope of the appended claims.

It is of course to be understood that the present invention is applicable to any type of boat or ship, from the largest steam vessels to the smallest hand propelled craft.

The use of the guiding rings for the anchors also render it possible to send down pontoons and air tanks which may be

slipped into the chains without the need for services of a diver.

I claim:

1. A ship having open-topped receptacles sunk in its deck, marking buoys received in said receptacles and normally lying flush with the deck, extended grooves in said deck for receiving chains, anchored at their ends to the ship, the intermediate portions of which are normally housed in the bottom of the compartment, and flexible devices connecting the buoys and the chains, said flexible devices adapted to serve as guiding means for guiding a grappling hook into engagement with the chains when salvaging the ship. 65 70 75 80

2. A ship having open-topped receptacles sunk in its deck, marking buoys received in said receptacles and normally lying flush with the deck, chains, anchored at their ends to the ship, the intermediate portions of which are normally housed in the bottom of the compartment, and flexible devices connecting the buoys and the chains, said flexible devices adapted to serve as guiding means for guiding a grappling hook into engagement with the chains when salvaging the ship, the deck being grooved to accommodate sections of the chains which are laid across the deck into the compartments. 85 90 95

3. A ship having open-topped receptacles sunk in its deck, marking buoys received in said receptacles and normally lying flush with the deck, extended grooves in said deck for receiving chains, anchored at their ends to the ship, the intermediate portions of which are normally housed in the bottom of the compartment, and flexible devices connecting the buoys and the chains, said flexible devices adapted to serve as guiding means for guiding a grappling hook into engagement with the chains when salvaging the ship, the marking buoys including flanged tops and centering pins on the deck engaging the tops of the buoys to retain the buoys against rotation in their receptacles. 100 105 110 115

4. A ship having open-topped receptacles sunk in its deck, marking buoys received in said receptacles and normally lying flush with the deck, extended grooves in said deck for receiving chains, anchored at their ends to the ship, the intermediate portions of which are normally housed in the bottom of the compartment, and flexible devices adapted to serve as guiding means for guiding a grappling hook into engagement with the chains when salvaging the ship, the chains entering the upper ends of the compartments and being disposed in grooves therein, whereby when the ship is submerged water may enter the compartments through the chain grooves to float the buoys upwardly. 120 125

5. A ship having open-topped receptacles sunk in its deck, marking buoys received in said receptacles and normally lying flush with the deck, extended grooves in said deck 5 for receiving chains, anchored at their ends to the ship, the intermediate portions of which are normally housed in the bottom of the compartment, flexible devices connect- ing the buoys and the chains, said flexible devices adapted to serve as guiding means 10 for guiding a grappling hook into engagement with the chains when salvaging the ship, drain pipes for carrying off water which may seep into the compartments, and a pump for removing the drainage water.

JEROME PASINI.
